Inventor,

Clifford E. Nadaud

UNITED STATES PATENT OFFICE.

CLIFFORD E. NADAUD, OF COVINGTON, KENTUCKY, ASSIGNOR TO INTERNATIONAL RIVER JORDAN WATER COMPANY, OF NEW YORK, N. Y.

DESIGN FOR A BOTTLE.

No. 38,696.

Specification for Design.

Patented July 23, 1907.

Application filed June 24, 1907. Serial No. 380,629. Term of patent 3½ years.

To all whom it may concern:

Be it known that I, CLIFFORD E. NADAUD, a citizen of the United States, residing at Covington, in the county of Kenton and State of Kentucky, have invented a new, original, and ornamental Design for a Bottle, of which the following is a specification, reference being had to the accompanying drawing, forming part thereof.

The figure is a plan view of a bottle, showing my new design.

I claim:

The ornamental design for a bottle, as shown.

CLIFFORD E. NADAUD.
